UNITED STATES PATENT OFFICE.

KATHARINE H. NOLAND-GARNETT, OF CHARLOTTESVILLE, VIRGINIA.

DESIGN FOR A BADGE.

SPECIFICATION forming part of Design No. 24,917, dated November 26, 1895.

Application filed June 5, 1895. Serial No. 551,787. Term of patent 14 years.

To all whom it may concern:

Be it known that I, KATHARINE H. NOLAND-GARNETT, a citizen of the United States, residing at Charlottesville, in the county of Albemarle, State of Virginia, have invented and produced a new and original Design for a Badge, of which the following is a specification, reference being had to the accompanying drawing, forming part thereof.

The leading feature of my design for a badge is an annular and cross flags within the same, the ends of the staff and outer sides of the flags joining the inner circumference of the annular.

In the drawing, A designates an annular rim, and B and C designate two flags therein.

The staffs D of the flags are crossed and join the rim A. The flag B is composed of longitudinal bars E and a field F with stars therein. The flag C is composed of vertical bars G and a field with the cross H therein and stars in said cross. The opposite ends of the flag-staffs and the outer sides of the flags join the inner circumference of the annular. 20

What I claim is—

The design for a badge substantially as described and shown. 25

KATHARINE H. NOLAND-GARNETT.
